UNITED STATES PATENT OFFICE.

RICHARD F. BEUTLICH, OF CHICAGO, ILLINOIS, ASSIGNOR TO THE 20TH CENTURY MACHINERY CO., OF CHICAGO, ILLINOIS, A CORPORATION OF ILLINOIS.

LABELING-MACHINE.

1,174,469.

Specification of Letters Patent.

Patented Mar. 7, 1916.

Application filed January 25, 1915, Serial No. 4,116. Renewed January 13, 1916. Serial No. 72,000.

To all whom it may concern:

Be it known that I, RICHARD F. BEUTLICH, a citizen of the United States, residing at Chicago, in the county of Cook and 5 State of Illinois, have invented certain new and useful Improvements in Labeling-Machines, of which the following is a specification, reference being had to the accompanying drawing, forming a part thereof.

10 This invention relates more particularly to wiping mechanism for wrapping labels around and pressing and smoothing them upon bottles or the like, as they are discharged from a labeling machine. Its main 15 objects are to facilitate wrapping, and to smoothly press the labels, especially long labels, upon the bottles or the like as they are ejected from the holders or carrier, and pass the gummers from which the labels are taken 20 with sufficient gum or paste to securely attach them to the bottles or the like, and generally to improve the construction and operation of devices of this class.

In the accompanying drawing like characters designate the same parts in the several figures.

Figure 1 is a side elevation of a wiper attachment embodying the invention, as applied to a labeling machine comprising a 30 bottle carrier provided with gummers at the sides of the bottle holders or receptacles, a reciprocating ejector for removing the bottles from the carrier, a clamp for holding the labels centrally against the bottles as 35 they are ejected from the machine, and a delivery table on which the bottles are discharged, the carrier being shown in section on the line 1—1, Fig. 3; Fig. 2 is a view partly in front elevation and partly in vertical section on the line 2—2, Fig. 4; Fig. 3 is a plan view showing the wipers in normal position and a bottle in position in the carrier to be ejected between the wipers; and Fig. 4 is a similar view showing a bottle in 40 its passage between the wipers, the springs at the upper ends of the wiper spindles being omitted and the spindles shown in cross section in Figs. 3 and 4.

The labeling machine to which the wiper attachment is applied comprises an intermittently movable bottle carrier, which may consist as shown, of bottle holders or receptacles 1, linked or pivoted together, as shown in Figs. 1 and 3, and provided at the sides

with gummers 2; a reciprocative ejector 3, 55 adapted to thrust or remove the bottles from the holders between the gummers while they are at rest opposite the wiper attachment, a clamp 4 for pressing and holding the labels centrally against the bottles as they are 60 ejected from the carrier between the gummers; and a delivery table 5, upon which the bottles are discharged from the carrier. The carrier as shown, is supported and guided on a horizontal bed plate 6.

65 As illustrated, the machine is designed to simultaneously apply both body and neck labels to the bottles, the bottles being designated by the numeral 7, the body labels by the numeral 8, and the neck labels by the 70 numeral 9.

The carrier with its bottle holders or receptacles 1, the ejector 3 and the clamp 4, may be constructed in various ways and operated by any suitable means (not shown), 75 such for example, as are shown and described in the application of H. M. A. Harders, Serial No. 679,927, filed February 26, 1912.

80 As shown, the gummers, which are located on the outer side of the carrier and on opposite sides of the several bottle holders or receptacles 1, are preferably offset at their upper ends toward the inner side of the carrier, as shown in Figs. 1, 3 and 4, to 85 carry the labels 8 and 9 close to the bodies and necks of the bottles 7 within the holders.

The clamp 4 may consist as shown, of an angular arm pivoted to the upper end or part of the ejector 3, so as to be turned down 90 and up into and out of operative position, and it is provided in different planes with pads 10 and 11 corresponding in position with the lower and upper parts of the gummers for pressing and holding the body and 95 neck labels 8 and 9 against the bodies and necks of the bottles 7 midway between the gummers as the bottles are thrust by the ejector from the carrier between the gummers.

100 The wiper attachment comprises two standards 12, mounted on the delivery table 5 approximately opposite the gummers 2 as they are brought to rest with each bottle holder or receptacle 1, in discharging position. Vertical spindles 13 are journaled in the bases and upper overhanging ends of the standards 12 parallel with each other, and

are provided at their lower ends with arms 14 secured thereon by set screws 15, and projecting normally inward, as shown in Fig. 3, into the path of the ejected bottles. These 5 arms are preferably provided at their inner ends with rollers 16 for contact with the bottles. At their opposite ends they are extended and form stops 17, which by engagement with the standards 12, as shown in 10 Figs. 1 and 3, limit the outward angular movement of the spindles with the wipers mounted thereon, as hereinafter explained.

At their upper ends the spindles 13 are provided, as shown in Figs. 1 and 2, with 15 spiral springs 18, which connect them with the standards 12 and tend to turn the stops 17 outward and to hold them in engagement with the standards, as shown in Fig. 3.

Vertically and angularly adjustable sleeves 20 19 are mounted on the spindles 13 and are secured in adjusted position thereon by set screws 20. These sleeves are provided at the ends with collars 21 and 22, the collars 22 being detachable and angularly adjustable, while the collars 21 are fixed relative to the sleeves and may be made integral therewith. The collars 22 are secured in adjusted position on the sleeves by set screws 23. Wiper arms 24 are pivotally mounted on the sleeves 19 next to the fixed collars 21 at their lower ends, and are connected by spiral springs 25 encircling the sleeves with the adjustable collars 22 in such a manner as to tend to turn the wiper arms inwardly relative to the spindles, or permit the wiper arms to yield outwardly. To the inner or free ends of the arms 24 are attached fingered wipers 26, made of flexible or elastic material such as rubber and adapted to interlock or close together when they are turned inwardly to the extent of their inward movement.

The inward movement of the wipers is limited independently of the angular inward movement of the spindles 13 by stop lugs 45 27 on the hubs of the arms 24, and adjustable stops 28 attached to the standards 12. The stops 28 may consist as shown, of rods tightly fitted and adjustable lengthwise in shouldered eye-bolts 29, which are adjustable in vertical slots 30 in the standards 12, and are secured in place therein by nuts 31. The inner angular movement of the wipers 26 relative to the spindles 13 is limited, and the outer or normal positions of the wipers 55 when the stops 17 are held by the springs 18 in engagement with the standards 12, as shown in Fig. 3, are determined by lugs 32, projecting from the collars 21 into position 60 to engage with the lugs 27 on the wiper arms. The wipers 26 are designed to apply body labels 8 to the bottles 7, or the like.

For applying the neck labels 9, an extra 65 pair of wipers, 33, like or similar in construction to the wipers 26, is provided.

These wipers are attached to the inner or free ends of arms 34, which are pivotally mounted on sleeves 35. The sleeves 35 are angularly and vertically adjustable on the spindles 13, and are secured in place thereon by set screws 36. Like the sleeves 19, the sleeves 35 are provided at the ends with collars 37 and 38, the collars 38 being angularly adjustable with relation to the sleeves 35, and secured in place thereon by set screws 39.

The arms 34 are mounted on the upper ends of the sleeves 35, and are connected by spiral springs 40 surrounding the sleeves, with the collars 37, in such a manner that the springs tend to turn the wipers inwardly relative to the sleeves or spindles, or permit the wipers to yield outwardly relative to the spindles. The upper ends of the sleeves 35 are reduced in diameter to form shoulders between which and the collars 38 the hubs 85 of the arms 34 are loosely confined. The hubs of the arms 34 are formed or provided with stop lugs 41, which by engagement with stops 42 limit the inward movement of the wipers 33. The stops 42, like the stops 28, 90 may consist of pins or rods adjustable lengthwise in threaded and shouldered eye-bolts 43, which are adjustable vertically in the slots 44 in the standards 12, and are secured in place therein by nuts 45.

The collars 38 are formed or provided with lugs 46, overhanging the hubs of the wiper arms 34 and adapted by engagement with the lugs 41 to determine the initial or normal position of the wipers 33 when the 100 stop arms 17 engage with the standards 12, as shown in Fig. 3, and to limit the inward angular movement of the wipers relative to the spindles 13.

In the operation of the machine as hereinbefore described, bottles 7 being placed in the holders or receptacles 1 of the carrier, and labels 8 and 9 applied to gummers 2 across the spaces between them through which the bottles are ejected, the gummers 110 being previously supplied with gum or paste by the usual or any suitable means (not shown), as each holder 1 comes to rest opposite the wipers, the ejector 3 is advanced, thrusting the bottle from the carrier between the gummers on the delivery table 5, as illustrated in Figs. 3 and 4. Simultaneously with the advance of the ejector 3, the clamp 4 is turned downward, carrying the pads 10 and 11 into engagement with the central portions of the labels and pressing them against the body and neck of the bottle on the front or advancing side thereof. As the bottle is advanced from the position in which it is shown by full lines, to the position indicated by dotted lines in Fig. 3, the ends of the labels are stripped from the gummers and pass between the wipers 26 and 33, by which they are turned backward 125 against the sides of the bottle body and neck. 130

In passing from the position indicated by dotted lines in Fig. 3, to the position shown by full lines in Fig. 4, the body of the bottle engaging with the rollers 16, turns the arms 14 forward and the wipers 26 and 33 inward, pressing the ends of the labels smoothly against and wrapping them around the back of the bottle body and neck to which they are attached by the paste or 5 gum taken from the gummers 2. At the limit of the inward and forward movement of each pair of wipers, when they are turned into approximately the same plane and their fingers interlock or close together, as shown 10 with respect to the wipers 33 in Figs. 2 and 4, the stop lugs 27 or 41 on the wiper arms engage with the stops 28 or 42, thereby arresting further movement of the wipers, while the arms 14 with the spindles 13 are 15 permitted to turn further in the same direction to allow the bottle to pass between and clear the rollers 16. The inward and forward movement of each pair of wipers is limited independently of the other, according 20 to the adjustment of the stops 28 and 42. When the bottle has been moved forward by the ejector 3 far enough to clear the rollers 16, as indicated by dotted lines in 25 Fig. 1, the springs 18 turn the spindles 13 with the wipers back to their initial positions, as shown in Fig. 3, for operation on another bottle, the backward and outward movement of the wipers with the spindles 13 and their arms 14 being limited by the 30 engagement of the stop arms 17 with the standards 12. As the arms 14 are turned forward by the engagement therewith of an ejected bottle, the wipers are turned inward and yieldingly pressed with the label against 35 the bottle body and neck, following their curved surfaces from the sides around to the center of the back when the fingers of the wipers are brought together, completing the wrapping of the labels around the body and 40 neck of the bottle.

During the foregoing operations, as the arms 14 are turned forwardly by the passage of the bottle between them, the arms of each pair of wipers yield outwardly and 45 backwardly independently of the arms of the other pair of wipers, against the tension of the springs 25 and 40, the lugs 32 and 46 being separated more or less from the lugs 27 and 41 on the wiper arms, according to the size and shape of the bottle or 50 variations therein, and the adjustment of the wiper mechanism.

The wipers 26 are adjusted vertically for 55 bottles of different sizes and for varying the location of the body labels thereon by simply loosening the set screws 20 and shifting the sleeves 19 up or down on the spindles, the sleeves being secured in their adjusted 60 positions on the spindles by tightening said screws, and the stops 28 being adjusted cor-

respondingly to properly cooperate with the lugs 27 on the wiper arms 24. The angular relation of the wipers 26 to the stop arms 17 may be varied to adjust the initial position of the wipers for bottles of different sizes or 70 diameters, by loosening the set screws 20 and turning the sleeves with the lugs 32 bodily on the spindles 13. The tension of the springs 25 is adjusted by the angular adjustment of the collars 22 on the sleeves 19. 75

The wipers 33 and their stops are similarly adjusted, but independently of the wipers 26. The collars 38 are adjusted on the sleeves 35 with relation to the spindles 13, so that the lugs 46 by engagement with 80 the lugs 41, will turn the wipers 33 into their initial positions and hold them in the desired angular relation to the spindles when the stop arms 17 engage the standards 12, as shown in Fig. 3, and being held in such positions, the tension of the springs 40 may be varied by turning the sleeves 35 in the collars 38 and on the spindles, the set screws 36 and 39 being tightened when the desired 85 adjustments have been effected. 90

Various changes in the details of construction and arrangement of parts may be made without departing from the principle and scope of the invention as defined in the following claims. By the term "bottle" as 95 herein used, it is intended to include receptacles or packages of various materials and different shapes, such as tin cans, to which labels may be applied in machines of this character. 100

I claim:

1. In a labeling machine the combination with a bottle holder and an ejector adapted to remove a bottle laterally therefrom, of wipers pivotally mounted on opposite sides 105 of the path of a bottle as it is ejected from the holder, and arms connected with the wipers, projecting into the path of the ejected bottle and adapted by engagement therewith to turn the wipers inwardly against the bottle and to press and wrap a label about the same as it passes between them. 110

2. In a labeling machine the combination with a bottle holder and an ejector adapted 115 to remove a bottle laterally therefrom, of wipers pivotally mounted on opposite sides of the path of a bottle as it is ejected from the holder, arms yieldingly connected with the wipers, projecting into the path of the ejected bottle and adapted by engagement therewith to turn the wipers inwardly and wrap and press a label against the back of the bottle as it passes between them, and stops for limiting the inward and outward 120 movement of the wipers. 125

3. In a labeling machine the combination with a bottle holder having gummers on opposite sides of a discharge opening and an ejector adapted to remove a bottle from 130

the holder through said opening, of pivoted wipers having their axes parallel with and opposite the gummers in the discharging position of the holder and projecting normally inward toward the bottle in the holder, and arms connected with the wipers and adapted by engagement with the bottle as it passes between the wipers to turn them inwardly and cause them to wrap and press the ends of a label taken by the ejected bottle from the gummers against the back of the bottle.

4. In a labeling machine the combination with a bottle holder having gummers at the sides, an ejector adapted to remove a bottle from the holder between the gummers and a clamp for holding a label against the front of the bottle as the bottle passes between the gummers and the label is withdrawn from the gummers, of pivoted wipers having their axes parallel with and opposite the gummers in the discharging position of the holder, and arms connected with the wipers and adapted by engagement with the ejected bottle to turn them inwardly and cause them to wrap and press the ends of the label against the back of the bottle.

5. In a labeling machine the combination of oscillating spindles arranged on opposite sides of the path of bottles as they are ejected from the machine and substantially parallel with the axes of the ejected bottles, wiper arms pivotally mounted on said spindles and provided at their free ends with flexible wipers, springs connecting said arms with the spindles and permitting the arms to yield outwardly, stops on the arms and spindles for limiting the inward angular movement of the wiper arms relative to the spindles, arms fixed on the spindles in the path of ejected bottles and adapted by engagement with a bottle to turn the wipers inwardly and cause them to wrap and press a label against the bottle as it passes between them, springs tending to turn the spindles with the wipers outwardly, and stops for limiting their outward movement.

6. In a labeling machine the combination of oscillatory spindles arranged on opposite sides of the path of bottles as they are ejected from the machine, wipers pivotally mounted on said spindles, collars angularly adjustable on said spindles, spiral springs connecting said collars with the wipers and tending to turn the wipers inwardly on the spindles, stop-collars angularly adjustable on said spindles and adapted by engagement with the wipers to limit their inward movement relative to the spindles, arms fixed on the spindles in the path of the ejected bottles and adapted by engagement therewith to turn the wipers inwardly and cause them to press labels around and against the backs of the bottles, springs tending to turn

the spindles and wipers outwardly, and stops for limiting the outward movement of the spindles and wipers.

7. In a labeling machine the combination of parallel oscillatory spindles on opposite sides of the path of ejected bottles, wipers pivotally mounted on said spindles, collars angularly adjustable on the spindles, spiral springs connecting said collars with the wipers and tending to turn the wipers inwardly relative to the spindles, angularly adjustable stop collars on the spindles adapted by engagement with the wipers to limit their inward movement relative to the spindles, arms fixed on the spindles in the path of the ejected bottles and adapted by engagement therewith to turn the wipers inwardly and cause them to press labels against the backs of the bottles, stops for limiting the inward movement of the wipers with the spindles, springs tending to turn the spindles with the wipers outwardly, and stops for limiting the outward movement of the spindles and wipers.

8. In a labeling machine the combination of parallel oscillatory spindles on opposite sides of the path of bottles ejected from the machine, flexible fingered wipers mounted on said spindles and adapted to interlock when turned inwardly, arms fixed on the spindles in the path of ejected bottles and adapted by engagement therewith to turn the wipers inwardly and cause them to press labels against the backs of the bottles, springs tending to turn the spindles with the wipers outwardly, and stops for limiting the outward movement of the wipers with the spindles.

9. In a labeling machine, comprising a carrier provided with bottle holders having gummers at the sides, an ejector for thrusting bottles from the holders between the gummers and a table on which the bottles are delivered from the carrier, the combination of standards mounted on the delivery table opposite the gummers in the delivery position of the holders, vertical spindles journaled in said standards parallel with each other and on opposite sides of the path of ejected bottles, wipers mounted on said spindles and vertically adjustable thereon, arms fixed on the spindles in the path of ejected bottles and adapted by engagement therewith to turn the wipers inwardly and cause them to press labels against the backs of the bottles, springs tending to turn the spindles with the wipers outwardly, stops for limiting the outward movement of the wipers and stops adjustably mounted on the standards for limiting the inward movement of the wipers.

10. In a labeling machine, comprising a carrier provided with bottle holders having gummers at the sides, an ejector for thrusting bottles from the holders between the

gummers and a table on which the bottles are delivered from the carrier, the combination of standards mounted on the delivery table, vertical spindles journaled in the standards parallel with each other on opposite sides of the path of ejected bottles, two pairs of wipers pivotally mounted and vertically adjustable on said spindles, springs tending to turn the wipers inwardly relative to the spindles, means for adjusting the tension of the springs, arms fixed on the spindles in the path of the ejected bottles and adapted by engagement therewith to turn the wipers inwardly and cause them to press labels taken by the ejected bottles from the gummers against the backs of the bottles, stops adjustable on the standards for limiting the inward movement of the wipers, springs tending to turn the spindles with the wipers outwardly, and stops for limiting the outward movement of the wipers.

11. In a labeling machine the combination of spindles on opposite sides of the path of bottles discharged from the machine, sleeves adjustable angularly and lengthwise on said spindles and provided at the ends with collars one of which is angularly adjustable

thereon, wipers pivotally mounted on said sleeves, spiral springs connecting the wipers with the collars at one end of the sleeves and tending to turn the wipers inwardly relative to the spindles, stop lugs on the other collars adapted by engagement with lugs on the wipers to adjustably limit the inward movement of the wipers relative to the spindles, stops adjustable on the standards adapted by engagement with the lugs on the wipers to limit the inward movement of the wipers independently of the spindles, arms fixed on the spindles in the path of the ejected bottles and adapted by engagement therewith to turn the wipers inwardly and cause them to press labels against the backs of the bottles as they pass, springs tending to turn the spindles with the wipers outwardly, and stops for limiting the outward movement of the spindles with the wipers.

In witness whereof I hereto affix my signature in presence of two witnesses.

RICHARD F. BEUTLICH.
